DOCTOR BLADE

Viggo Carlsen, Norwich, and Alwin Heinrich, Taftville, Conn., assignors to The Aspinook Corporation, Jewett City, Conn., a corporation of Delaware

Application January 16, 1945, Serial No. 572,998

1 Claim. (Cl. 101—153)

1. A doctor blade.

The present invention relates to doctor blades for use in textile printing machines and similar uses. More particularly, it relates to a doctor blade that is protected from corrosion from the action of the constituents of the printing pastes used in such printing, and which may be sharpened when such doctor becomes corroded without undue wear from the sharpening operation.

In printing textile fabrics, a copper roller that is engraved with the design to be printed rotates against a press cylinder and prints the design upon a cloth passing over the cylinder. The color paste is supplied by a furnisher roll that rotates against the engraved copper roller. The furnisher roll rotates in a font containing the printing paste and, as it contacts the engraved roll, deposits the color thereon. The engraved roll, however, when it rotates against the cloth to be printed, should have this color paste only in the depressions of the engraving, but the furnisher roll deposits color not only in the engraving but also wherever it contacts the engraved roll, both within and without the engraved design throughout its length. Accordingly, a sharp doctor blade is provided to clean the engraved roll, that is, to scrape off all the paste deposited thereon except where it is contained in the intaglio design.

This doctor blade is a razor sharp steel blade which is kept pressed against the engraved roll and which scrapes the excess paste therefrom so that it flows back into the font.

In general, textile fabrics are printed with vat colors, commercial colors (basics and alizarine) or aniline blacks. In printing with vat colors, the paste is alkaline whereas with commercial or aniline colors, the paste is on the acid side. These pastes are very corrosive and especially so the anilines, so that the edge of the doctor blade becomes eroded and uneven and unsuitable for performing its function.

As a result of this the doctor blade must be removed from the machine and refiled to sharpen its edge some times several times during a day's operation. This causes considerable loss of time in printing. Moreover, no matter what kind of paste is used, the moisture in the paste and in the air will have a corrosive action on the doctor blade, and it is common practice to remove all doctor blades at night and, before setting up the machines in the morning, all doctors must again be filed to a razor sharp edge and replaced, an operation that takes ordinarily an hour or two, all depending upon the number of rollers used.

These doctor blades are made of the best quality of medium tempered steel. They vary in

width from two to three inches, in thickness from $\frac{1}{2}$ to $\frac{1}{8}$ of an inch, and in length according to the length of the engraved roller, being usually some two inches longer. Their top or working edge, i. e., the edge that contacts the roller, is filed to a suitable bevel and then sharpened by hand with an oil stone to a razor-like keenness. Their bottom edges are firmly clamped between two brass holders, or one of brass and one of iron, 5 tightly screwed together and furnished at each end with a supporting pivot that rests on a bracket attached to the bearing of the roller, and a projecting lever by means of weights or screws serves to press the blade on the roller.

10 In order to prevent the unequal wearing of their sharp edges, which would occur if they were allowed to rest continuously in one position on the roller, the doctor blades are given a slight to and fro movement in a direction parallel to the axis of the roller. Notwithstanding all these precautions, however, the edge of the doctor blade in a comparatively short time becomes uneven due to corrosion, and when this happens, streaks of color pass under the doctor and cause smears upon the cloth that is being printed. They then 15 must be removed and resharpened.

Here, again, frequent sharpening of the doctors causes a wearing down and finally a wearing out of the blades. In sharpening, the printer not 20 only goes over the bevelled face of the doctor with a file and stone, but he also must "face" it, that is, he must file and stone the bearing face that rests on the roller. This "facing" or filing of the bearing face wears down the original thickness of the blade and, after a certain amount of such wear is reached, the doctor blade must be discarded as it no longer will fulfill its purpose.

The sharpening or "getting up" of the edge 25 of the doctor blade is one of the most difficult and most important parts of the machine printer's work. The quality of this edge depends not only upon the weight and scale of the engraving but also upon the thickness and hardness of the doctor blade, the angle at which it rests upon the roller, the pressure applied to it, and upon 30 both the viscosity and density of the printing color which it has to clean off. Generally speaking, the edge of the well sharpened cleaning doctor is perfectly straight, absolutely smooth throughout its entire length, and bevelled to a rather obtuse angle. It is sharp as a razor and any roughness, unevenness or the slightest break 35 in the edge is sufficient to allow color to escape under it with the result that the finished print

exhibits serious defects in the form of streaks or cloudy patches of color.

It is an object of the present invention to provide a doctor blade which will be protected against corrosion to the greatest possible degree and which, nevertheless, can be maintained at the required razor sharpness of the present doctor blades.

It is a further object of the invention to provide a doctor blade that will not wear down readily under the sharpening operation and that as a consequence retains its thickness and hence its efficiency over a very long period of time.

By use of the doctor blades of the present invention, frequent resharpening is unnecessary and furthermore the doctor blade may be left in place on the printing machine all night and the work of printing can be resumed immediately in the morning. This results in a saving of many hours a day in printing operations and a substantially greater output of work from each machine.

Briefly described, the invention consists of providing a doctor blade having an edge bevelled in the usual manner to an obtuse angle and sharpened to a razor edge and having the face of the blade, that is, that side of the blade that rests on the roller, plated with a hard, smooth, corrosion-resisting metal such as chromium or tantalum. The plating is carried to the razor edge of the doctor blade on the bearing side so that the corrosive acids in the printing paste do not affect the steel edge of the blade. On the other hand, if after use, some small amount of corrosion of the edge of the doctor does take place, the master printer may remove it and resharpen it in the usual manner since the bevelled face of the blade is not plated. The plated side of the blade, however, will not wear under this sharpening, as the plating gives a very hard and smooth surface on which the file and stone will glide without biting into the metal. The coatings used for this purpose should be metals that are not only resistant to the action of acids but should have a very hard, smooth surface so that the bearing face cannot be filed or stoned. When so coated, the

doctor will not be worn thin under the sharpening operation.

In the drawing, Fig. I represents schematically the arrangement of the rolls on a textile printing machine with the doctor blade in place; Fig. II shows a doctor blade of the invention in detail.

Referring to Fig. I, 1 is the cylinder around which the blanket 2 is lapped. The cloth 3 which is being printed passes between the blanket 2 and the engraved roll 4. The furnisher roll 5 rotates in the font 6 and contacts the engraved roll 4 which rotates in reverse direction to the rotation of furnisher roll 5. The doctor blade 7 presses with its plated face 10 bearing against the engraved roll 4, thus scraping the color from said roll except where it fills the depressions of the engraving.

In Fig. II is shown the doctor blade with its holder or sheath 8, its steel body 9 and chromium or tantalum plating 10 on one side of the steel body.

It will be apparent that when a doctor of the present invention is sharpened by the printer, only the bevelled side of the blade will be filed and stoned, as neither the file nor the stone will make any impression on the hard, smooth chromium or tantalum coating on the bearing face. As a result, there will be little wear on the plated face and the surface on that side will always remain the same without loss of thickness of the blade. Such a plated doctor blade will have a life several times as long as the ordinary doctor blades now in use and in addition will retain its sharpness much longer, thus requiring fewer sharpenings.

Having thus described our invention, what we claim is:

A doctor blade comprising a steel backing bevelled down to a razor sharp edge and a plating of chromium on the unbevelled underside extending to the edge, the plated side of said edge being adapted and arranged to bear on a printing roller of a textile printing machine.
